CLAIM

The ornamental design for an infrared thermometer, as shown and described.

DESCRIPTION

FIG. 1 is a perspective view of an infrared thermometer showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof;

FIG. 9 is a perspective view of the infrared thermometer in an extended position; and,

FIG. 10 is an enlarged view of the encircled portion in FIG. 2.

The broken lines in FIG. 2 and FIG. 10 represent boundary lines and form no part of the claimed design.

1 Claim, 10 Drawing Sheets
